WASTE BASKET OR SIMILAR ARTICLE

Jon W. Hauser, St. Charles, Ill., assignor to Hawley Products Company, St. Charles, Ill., a corporation of Delaware

Application March 7, 1955, Serial No. 34,883

Term of patent 14 years

(Cl. D58—4)

FIG. 1

FIG. 3

Fig. 1 is a side elevational view of a waste basket or similar article, embodying my new design;

Fig. 2 is a front elevational view thereof; and

Fig. 3 is a top plan view thereof.

The essential feature of my design resides in the receptacle portion thereof.

I claim:

The ornamental design for a waste basket or similar article, substantially as shown and described.
